UNITED STATES PATENT OFFICE.

CHARLES H. RETTMANN, OF CHICAGO, ILLINOIS.

ELECTRORESPONSIVE VIBRATOR-MOVEMENT.

1,038,438.

Specification of Letters Patent. Patented Sept. 10, 1912.

Application filed January 7, 1911. Serial No. 601,400.

To all whom it may concern:

Be it known that I, CHARLES H. RETTMANN, a citizen of the United States, residing at Chicago, in the county of Cook and State of Illinois, have invented certain new and useful Improvements in Electroresponsive Vibrator-Movements, of which the following is a specification.

My invention relates to improvements in electro-responsive vibrator movements, and has for its general object to provide a movement particularly adapted for employment in high voltage circuits in connection with signal bells or the like, and having its electrical connections and contact devices so arranged that no spark is produced incidentally to the performance of its circuit-interrupting functions, and that its inductive effect in the line is minimized.

In the drawings, wherein I have shown the vibrator movement as applied to a signaling bell, Figure 1 is a front elevation of the bell with its cover removed; Fig. 2 is a section on line 2—2 of Fig. 1; Fig. 3 is a diagrammatic illustration of the movement and electric circuits; Fig. 4 is an enlarged plan detail of a friction device and its associated parts; and Fig. 5 is a section on line 5—5 of Fig. 1.

In the specific embodiment shown, I employ an electromagnet 10, whereof 11 is the yoke and 12 are the polar cores, the latter being wound with relatively differential windings 13 and 14, half of each said winding being preferably mounted upon each polar core.

15 indicates an armature pivoted upon a stationary pivot screw 16 for vibration in response to the action of the magnet and 40 a tractile spring. The pivoted end or heel of the armature 15 is conveniently provided with a contact leaf 17 preferably extending at right angles to the armature, and to its pivotal axis, for coöperation with a movable contact frame to be described. The contact frame 18, in the embodiment shown, comprises a limb 19, extending generally parallel with the armature contact leaf 17, and a second angularly disposed limb 20, 50 extending generally parallel with the armature 15, said frame being preferably pivoted coaxially with the armature for movement by said armature. To this end, the pivot screw 16, as best shown in Fig. 5, is 55 preferably headed, as at 16', and secured in a boss 21 of a bearing block 22, so that two

ears 23, suitably provided upon the frame 18 may engage boss 21 and the upper extremity of pivot 16 for pivotal movement free from frictional connection with the pivoted end of the armature. Further, it is preferable that the contact frame 18 should work a little stiffly on its pivot to prevent its movement save under compulsion of the armature, and to this end, I interpose a friction spring washer 24 of appropriate construction between the head 16' of the pivot screw and the upper ear 23 of the contact frame, as best shown in Figs. 4 and 5. The free end of spring limb 20 of frame 18 bears 60 a contact point 20' for coöperation with an adjustable back contact member 25, of customary screw design. The armature is provided with an insulated stop pin 26 to act against the contiguous face of frame limb 70 20, so that when the armature is retracted by its customary spring 27, said limb 20 is forced into contact, as at 20', with its co-acting contact member 25. Upon the limb 19 of said frame is provided an adjustable 75 insulated contact point 28, adjusted so that under normal conditions it is slightly removed from the contact 17' of leaf 17 of the armature. As a matter of advantageous embodiment of such movement in an electric bell, I mount all of the stationary parts of the movement structure upon an insulating base 30, surrounded by and secured to a metal rim 31, which projects sufficiently far beyond the back of the insulating base to 80 afford ample housing space for the connecting wires, terminal fastenings, and the like. Said rim 31 may conveniently carry an arm 32, on which is mounted the bell gong 33 to be actuated by a clapper 34 insulatedly 85 secured to the free end of armature 15.

35 indicates a sheet metal cover for the movement.

In the electrical connections of the parts heretofore described, two terminals 36 and 37 are conveniently provided upon the base 30 and from one of said terminals, 36, extend the wires 38 and 39, respectively connected to appropriate extremities of coils 13 and 14. The coil 13, which I will arbitrarily term the line coil, has its remaining extremity connected by wire 40 to the pivot structure 15—16, so that it is connected in common to the contact leaf 17 of the armature 15 and to the limb 20 of the contact frame 18. The back contact 25 for the limb 20 has connection by wire 42 to the remain-

ing line terminal 37. The remaining extremity of winding 14, which I will arbitrarily term the differential winding, is connected by wire 43 with the insulated contact point 28, carried by limb 19 of the contact frame 18, thus completing the interior connections of the movement.

The line terminals, 36 and 37, may be connected with the extremities of any appropriate line 45, and a circuit controlling device, such as a key or push button, 47.

Assuming the parts of the vibrator movement to stand in the normal position shown in Fig. 3, closure of the line connections by key 47 establishes a circuit as follows: from generator 46 by line 45+ and key 47 to terminal 36, by wire 38 through coils 13 to wire 40, through the spring limb 20 of the movable contact frame, to binding post carrying back contact 25, thence by wire 42 to terminal 37, and through the line 45—back to the generator. The coils 14 are not included in circuit because their circuit connections are now open between the contact 28 and the armature leaf 17. Consequently, the electromagnet effectively is energized by inclusion of its line coils 13 in the circuit, and said magnet attracts its armature 15. As the armature moves toward the magnet 15 poles, its contact leaf 17 engages contact 28, so effecting connection of the differential coils 14 with the line, in parallel with coils 13, the circuit connections being from line terminal 36 by wire 39, coils 14, wire 43, contact 28, and armature leaf 17, to limb 20 of the contact frame and thence by back contact 25 and wire 42 to the opposite terminal 37. The differential action of the coils 13—13 and 14—14 substantially and effectively deenergizes the magnet 15, but the momentum of the armature carries the leaf 17 farther upward, so that its action upon the limb 19 of the contact frame tilts said frame upon its pivot to move spring limb 20 out of connection with the back contact 25, so thus breaking the circuit for both of the windings. The coils, however, remain connected in a closed circuit local to the ringer movement, and traceable as follows: 36, 38, 13, 40, 17, 28, 43, 14, 39, 36,—so that the tendency of each coil to inductive discharge is neutralized by the other. Obviously with the circuit thus broken, armature 15 is quickly retracted by its spring, 27, 55 restoring the parts to initial position for another cycle of operations.

I find that where the magnet is effectively deenergized by differential connection of its two windings as a condition precedent to the complete breaking of the energized circuit, no spark at the circuit breaking terminals occurs at the break, even where high voltage, say 110 volts, is employed. Further, I find that the breaking of the circuit, subsequent to the neutralizing of the mag-

net, by a differentially connected coil is advantageous in producing a very quick-acting vibrator movement, and the series connection of the differential coils in local non-energized circuit reduces the inductive effect of the device in the line.

It will be observed that the specific construction disclosed is of simple, compact, and mechanically efficient form, features of which may hereinafter be claimed for their special advantage, but it will be apparent to those skilled in the art that many changes in the construction and arrangement might be made without departure from the broader aspects of my invention and within the scope of the appended claims.

What I claim is:

1. In an electro-responsive vibrator, the combination of a magnet having coils that magnetically oppose each other, suitable circuit connections normally including one of said coils, an armature, and contact devices actuated by said armature to establish circuit connections for the other coil and subsequently to break the circuit connections for both said coils.

2. In an electro-responsive vibrator, the combination of an electromagnet having windings that magnetically oppose each other, a normally closed contact device, a normally open contact device, circuit connections for one of said windings, normally including the closed contact device, and closed thereby, circuit connections for the other said winding including both said contact devices, and normally opened by the open contact device, and means responsive to uni-directional movement of said armature first to close the normally open contact device and subsequently open the normally closed contact device.

3. In an electro-responsive vibrator, the combination of an electro-magnet having windings that magnetically oppose each other, an armature having a contact leaf, a contact frame pivoted for movement by the armature leaf, and circuit connections including a normally open contact device local to the connections of one winding and closable by the armature leaf, and a normally closed contact device common to the connections of both windings arranged to be opened by armature-impelled movement of the contact frame.

4. In an electro-responsive vibrator, the combination of an electromagnet having windings that magnetically oppose each other, a pivoted armature therefor, a contact frame pivoted coaxially with the armature, a fixed contact for one end of said frame, a contact for the other end of said frame movable with the armature to close a circuit and thereafter move the frame, circuit connections for one winding including both the normally opened and the normally closed

contacts, and circuit connections for the other winding including only the normally closed contacts.

5. In a device of the character described, the combination of an electromagnet having windings that magnetically oppose each other, a base, an armature and a contact frame each mounted for movement upon said base, a normally open contact device 10 arranged to be closed by movement of said armature, the armature providing a member for abutment against the frame to cause contact-opening movement thereof, a normally closed contact device arranged to be 15 opened by such movement of the frame, and a circuit connection including said normally closed contact device and having a branch for each winding, one branch including and one branch excluding said normally open contact device.

29 6. In a device of the character described, a base, an electromagnet upon the base hav-

ing windings that magnetically oppose each other, a pivot post, an armature and a frame each mounted for pivotal movement upon 25 said post, a contact device normally closed by the frame, a normally open contact device having one member upon said armature and the other member upon said frame, said members adapted and arranged to engage 30 upon movement of the armature, and said frame adapted and arranged to be moved by such engagement to open said normally closed contact device, and a circuit including 35 said normally closed contact device and having a branch for each winding, one branch including and the other excluding said normally opened contact device.

In testimony whereof I hereunto set my hand in the presence of two witnesses.

CHARLES H. RETTMANN.

In the presence of—

FORÉE BAIN,
MARY F. ALLEN.
